CONSTANT BAND WIDTH RECEIVER

Joseph L. Bonanno, Forest Hills, N. Y., assignor
to Radio Corporation of America, a corpora-
tion of Delaware

Application August 20, 1929, Serial No. 387,149

9 Claims. (Cl. 178—44)

My present invention relates to couplings for radio circuits, and, more particularly, to a method of, and means for, maintaining a constant band width in a radio receiver.

5 In my co-pending application, Serial No. 387,148 filed August 20, 1929, there has been disclosed a system of coupled circuits in which capacity coupling is employed. The capacity coupling in the said system is obtained by employing auxiliary rotor plates secured to the usual rotor shaft of the bath-tub type of gang condenser, the auxiliary plates being insulated from the rotor shaft. As shown in the said co-pending application the auxiliary plates are electrically connected with each other, and are so shaped, and disposed relative to the end stators of each sectional condenser in the gang condenser, that rotation of the rotor shaft not only tunes the receiver stages, but simultaneously varies the capacity between the said end stators of the tuning condensers in such a manner that a constant band width is maintained throughout a given frequency range.

It is to be understood hereinafter that the expression "constant band width" refers to the constancy of width of the accepted, or selected, desired band of frequencies throughout the frequency range of a radio receiver. In other words, the short expression, "constant band width" is employed herein to describe the character of the band transmitted through a receiver provided with a band pass tuning network. This selected band of frequencies has the same width at all times regardless of which portion of the broadcast frequency range the receiver is tuned to.

However, the range of capacity required for constant band width in the usual broadcast reception receiving circuit may be quite large. Accordingly, unless mechanical complications are resorted to, it is difficult to secure a sufficiently small minimum capacity. Now, I have devised a method and means whereby it is unnecessary to resort to mechanical expediencies in order to overcome the aforementioned difficulty.

45 Accordingly, it is one of the main objects of my present invention to provide a receiver circuit in which constant band width is maintained throughout a given range of frequencies, a sufficiently small minimum capacity being secured without resorting to mechanical complications, regardless of the fact that the range of capacity required may be quite large.

Another important object of the invention is to maintain a constant band width in a receiver 50 circuit including a plurality of radio stages, the cou-

pling between radio stages being secured by variable capacity means, the inductance coils in each stage and the capacitive coupling between coils being so designed that the over-all coupling between stages may be brought to zero, or even reversed in phase, at any setting of the variable capacitive coupling.

Other objects of the invention are to improve generally the simplicity and efficiency of couplings, and to provide a coupling for radio circuits which is reliable in operation, follows a predetermined law of variation through a given frequency range, and is capable of adjustment to a sufficiently small minimum capacity where the coupling is capacitive and the range of capacity required is quite large.

The novel features which I believe to be characteristic of my invention are set forth in particularity in the appended claims, the invention itself, however, as to both its organization and method of operation will best be understood by reference to the following description taken in connection with the drawing in which I have indicated diagrammatically a circuit organization whereby my invention may be carried into effect.

In the drawing Fig. 1 schematically shows a circuit employing capacitive coupling between stages, as disclosed in the copending application referred to above,

30 Fig. 2 is a diagrammatic view of the type of circuit shown in Fig. 1, embodying my present invention,

Fig. 3 is a view of a detail, partly in section, of the invention,

35 Fig. 4 is a side elevation of Fig. 3, looking in the direction of the arrow.

Referring to the accompanying drawing in which like characters of reference indicate the same parts in the different figures, there is schematically shown in Fig. 1 a receiver circuit, as disclosed in my said co-pending application. I will only briefly describe this circuit, as the same is clearly disclosed in said application.

The grounded antenna circuit A, G is coupled, 45 as at M, to a conventional radio frequency amplifier, the output of the latter being capacitively coupled to the input of a subsequent stage and translating device. The coupling includes coil L₁ shielded as at T₁, a coil L₂ shielded as at T₂, 50 and a tuning gang condenser so connected between the coils that each condenser section of the gang, is shunted across its respective coil, the adjacent end stators of the condenser sections providing the capacity C_o.

The latter is varied by means of a special plate, or plates, mounted to rotate with the rotor shaft of the gang, and designed to vary the coupling between stages simultaneously with tuning of the stages, the variation being such as to maintain a constant band width over the entire desired frequency range.

Where the range of capacity is quite large, it is possible to secure a sufficiently small minimum capacity by an arrangement as disclosed in Fig. 2. A few turns of wire are added to the coils L_1 and L_2 , as shown at A and B. Thus, if points A and B represent the ends of the coils L_1 and L_2 in Fig. 1, these points are connected and grounded as shown in Fig. 2.

The end of coil L_1 (that is, coil L_1 in Fig. 2, represents coil L_1 in Fig. 1 plus a few turns) is connected to the capacity C_e , through a small fixed capacity C_n . The end of coil L_2 is connected to the opposite side of capacity C_e through a small capacity C'_n .

The variable capacity C_e is secured by mounting special rotor plates on the common rotor shaft of condenser C_1 and C_2 , and employing these plates to vary the capacity between end stators of adjacent section condensers, as disclosed in my said co-pending application.

In Figs. 3 and 4 is shown the manner of varying the capacity coupling C_e simultaneously with the tuning means, such means being substantially similar to Figs. 4 and 4a of my aforementioned co-pending application, Serial No. 387,148, filed August 20, 1929. Briefly, this means comprises the usual gang condenser common shaft 2 which has mounted on it a plurality of rotor plates R_1 of one condenser section, and a plurality of rotor plates R_2 of an adjacent section. The stator plates S_1 and S_2 mesh with their respective rotor plates.

The metallic housing 1, of the well known bath-tub design, is to be understood as supporting the rotatable metallic shaft 2 in metallic bearings, not shown. The plates R_1 and R_2 are, of course, electrically connected to the shaft 2, thereby grounding them. A metallic, shielding partition 5 is disposed between the adjacent end stator plates 9 and 10 of the adjacent condenser sections. The normal electro-static coupling between the plates 9 and 10 is, therefore, practically zero, due to the grounded partition 5. The stator plates S_1 and S_2 of each section are, of course, insulated from the metallic housing by spacers 2 of any well known type of insulation material.

The normal capacity coupling C_e , between the adjacent end stators 9 and 10 being zero, the coupling may be increased, and made any desired value by the auxiliary metallic rotor plates P_1 and P_2 mounted on shaft 2. Thus, between the end stator of each condenser section and the partition 5 is disposed an auxiliary plate. Both plates P_1 and P_2 are electrically connected by a metallic sleeve 6', the sleeve being insulated from the shaft 2 by the cylindrical insulator bushing 6.

In Fig. 4 there is shown the relation between the areas of the partition 5, the plates P_1 and P_2 , and the stator plates 9 and 10. All the capacity coupling is determined by the plates P_1 and P_2 , and, thus, by proper design any predetermined band width can be transmitted between the amplifier stages, and in this case a constant band width is maintained throughout the frequency range.

The over-all coupling between stages, at any position of condenser C_e may be brought to

zero, or even reversed in phase, by inserting the small capacities in the arrangement shown. Thus, if the minimum over-all coupling capacity is 1 micro microfarad, and a value of one tenth this amount is desired for maintaining a constant band width, the condensers C_n and C'_n are adjusted until the over-all coupling is decreased by 0.9 micro microfarad. This results in a net coupling of 0.1 micro microfarad.

The condensers C_n and C'_n are employed to retain symmetry of the circuits, i. e., tuning line-up. By over-all capacity is meant all coupling capacity due to the wiring, the coupling capacity C_e and the condensers C_n and C'_n . The fewer the number of turns added to each coil L_1 and L_2 , the larger can the capacities C_n and C'_n be; thus, facilitating adjustment.

While I have indicated and described a system for carrying my invention into effect, it will be apparent to one skilled in the art that my invention is by no means limited to the particular organization shown and described, but that many modifications in the circuit arrangements, as well as in the apparatus employed, may be made without departing from the scope of my invention as set forth in the appended claims.

What I claim is:

1. A method of operating adjacent tuned radio stages through a predetermined range of frequencies which consists in capacitively coupling the adjacent stages, varying the coupling simultaneously with the tuning of said stages, and adjusting the overall coupling capacity to a minimum.

2. A method of operating a plurality of tuned radio stages through a predetermined range of frequencies which consists in capacitively coupling said stages, varying said coupling simultaneously with the tuning of said stages, the coupling variation being such that a constant frequency band width is received at any frequency within said range, and maintaining the over-all coupling capacity at a minimum for each frequency.

3. A receiver comprising a plurality of radio stages, means for tuning each of said stages, means for coupling adjacent stages, means for varying the coupling between adjacent stages simultaneously with variation of said tuning means, the coupling variation being such that a constant frequency band width is received over the tuning range and additional adjustable means electrically connected between adjacent stages for reducing the over-all coupling characteristic to a minimum for a given frequency.

4. In a receiver, as defined in claim 3, said additional means being capacitive, said stages being additionally conductively connected.

5. In a receiver, a plurality of radio stages, means for tuning each of the stages, each of said stages including an inductance, said inductances being directly connected, means for capacitively coupling the stages, said coupling means being variable with the tuning means, the coupling variation being such that a constant frequency band width is received over the tuning range and additional capacitive means electrically connected between said stages for reducing the over-all coupling characteristic to a minimum for a given frequency.

6. In combination, in a tunable radio frequency band pass network, a pair of resonant oscillation circuits each including a coil and a variable tuning condenser, a common operating shaft for the rotors of both condensers, means,

operative with said shaft, for regulating capacity coupling between the circuits provided by inter-electrode capacity between said condensers, and fixed auxiliary condensers connected between 5 said circuits for neutralizing a desired portion of said coupling capacity.

7. In a receiver, a source of radio frequency signal energy, a succeeding signal transmission network, said network including at least two tunable signal circuits, each circuit including an 10 adjustable tuning reactance, an adjustable reactance for coupling the tunable circuits, a common means for adjusting said coupling reactance with the tuning reactances in such a manner that a substantially constant signal frequency

band width is transmitted through said network over the receiver tuning range, and additional means for securing a sufficiently small minimum coupling reactance value between the tunable circuits when said range is small. 5

8. In a receiver as defined in claim 7, said additional means comprising a pair of auxiliary reactances of the same sign.

9. In a receiver as defined in claim 7, said additional means comprising a pair of auxiliary reactances which are independent of said adjustable coupling reactance but of the same sign as the latter. 10
